Thomas W. J. Clark ATTORNEY

UNITED STATES PATENT OFFICE

WILLIAM J. ZULK, OF PHILADELPHIA, PENNSYLVANIA

SHOULDER-PRESSING BOARD

Application filed May 16, 1929. Serial No. 363,590.

My invention relates to improvements in a pressing board, and is particularly directed to a coat shoulder pressing board, and its objects are to make a board substantially the shape 5 of a person's shoulder, so that the coat will not be stretched out of shape in the pressing operation. Pressing boards must be strong and rigid, and another object of my invention is to make a board that may be revolved 10 end for end very easily and rapidly and that may be held firmly on its base in either of its positions. Due to this ease of revolution, the board is equally useful to a right handed or a left handed person. Other objects and 15 advantages will be apparent as the description continues.

In the accompanying drawings forming a part hereof,

Figure 1 is a top plan view of the board 20 showing the base in dotted lines.

Fig. 2 is a front elevation thereof.

Fig. 3 is a vertical sectional view on line 3—3 of Fig. 1.

Fig. 4 is a vertical sectional view on line 25 4—4 of Fig. 1.

Similar numerals refer to similar parts throughout the several views.

The board 1 has upon it a padding 2, and the board is pivoted on a bolt 3, the head of 30 which is countersunk into the board and is held down by plate 4 screwed to the board.

The board is supported on block 5, through 35 which the bolt 3 passes to recess 6. Bolt 3 has pinned washers 7 and 8 on both sides of lever 9, through which the bolt passes, at its lower end. Lever 9 is supported pivotally, by bolt 10, fast in block 5. Spring 11 is between a washer on the center part of the bolt 40 against block 5 and rests upon washer 7 and it firmly holds the board down onto the block 5.

Lever 12 is pivoted to the front of the block. This lever in its released position, 45 leaves lever 9 in its lower position and the spring effective to hold the board down tightly. When lever 12 is lowered, as in dotted lines in Fig. 3, it locks lever 9 up, the lever pushing the bolt 3 up against the action of the spring and the board 1 is up as in Fig. 3

so that it may be turned end for end, then lowered by releasing the lever 12.

Block 5 should be securely bolted to a table 13, or other support, as by bolts 14. At each end of board 1 and block 5 are fixed countersunk interlocking members 15 and 16, which hold the board firmly on the block when the lever 12 permits the spring 11 to hold the board down. 55

Block 5 is cut away at 17 to permit articles 60 to slip further over the board.

The board at its ends is shaped like a plan view of a person's shoulder. This shape may perhaps best be defined by the system of polar coordinates, although this system is used as 65 a medium of expression only, the conformity of the shape of the board to the plan view of a person's shoulders being the essential novelty. The ends, and the rear of the board from the ends, have a curve substantially like 70 that of one leaf of the three leaf lemniscate, which has the formula, $\rho = a \sin 3\theta$, in which ρ is the distance of any point on the curve from the pole, a fixed point of the system, θ is the angle between a fixed horizontal line through the pole and a line from the pole to the point on the curve, and $-a$ 75 is the length of a single leaf of the figure, called a lemniscate. If the leaf have its pole at the back of the board, as at 17, a central part of the board being substantially rectangular, and the large end of the leaf form the end of the board, as at 18, and the rear edge of the leaf be substantially in line with the rear edge of the rectangular center portion of the board for a distance from the leaf pole of about $\frac{1}{3}$ the length of the leaf, as at 19, and if the rectangular part of the board stop 80 at that point, at both the front and back parts of the board, and if a point 20, be taken on the front edge of the leaf which is cut by a line about $\frac{5}{6}$ of the length of the leaf from its pole, as at 21, and that point be joined by 85 a wave curve as at 22, to the front of the rectangular center portion, the shape of the board will, substantially, be produced. The depth of the board at its center portion, from front to back, is substantially $\frac{7}{12}$ the length of the leaf of the lemniscate. This description 90 applies to one end of the board. The relative 95

100

length of the board is immaterial except for the matter of convenience in use.

The board is designed primarily to press the top and top seam of the coat shoulder, and the coat shoulder is placed over the board end with the parts below the shoulder, that is, the sleeve and coat body, hanging downwardly from the board. The board is the shape of the plan view of a person's shoulder, the concave front part of the board end corresponding to the hollow in the front of the shoulder and the convex rear part of the board corresponding to a plan view of the scapula of a person's shoulder. This permits the pressing of the top front of the coat shoulder not only without bulging it outwardly, but it is kept in its exactly proper shoulder shape; the top back of the coat shoulder is likewise kept in its proper shape.

20 Unless the operative be ambidextrous, after pressing one shoulder, the board is turned end for end horizontally, and the other shoulder is then pressed in the same manner.

I have illustrated and described my improved board and its operating mechanism in detail in the form preferred by me on account of its structural simplicity and economy and convenience in use. I am, however, aware that it is capable of considerable variation in structural detail without departing from my invention.

What I claim as new and desire to secure by Letters Patent is:

1. A support for a pressing board, an opening therein, a bolt passing through said opening and to which the board is revolubly attached, a lever fulcrumed at one end and having means to raise the lower end of said bolt, a compression spring held between the lever and the support, whereby the board is held tightly down on said support, and means to compress said spring and raise said bolt, whereby the board may be revolved.

2. A support for a pressing board, an opening therein, a bolt passing through said opening and to which the board is revolubly attached, a lever fulcrumed at one end and having means to raise the lower end of said bolt, a compression spring held between said lever and the support, and a lever to elevate and compress said first named lever, whereby said bolt is raised and the board may be revolved and then held again firmly in its revolved position.

3. A shoulder pressing board having a substantially rectangular center portion, an end portion substantially the shape of one leaf of a lemniscate of the formula $\rho = a \sin 3\theta$, in which the pole of the lemniscate is at the rear edge of the rectangular center portion, and the rear side of the rectangular center portion is substantially tangential to the rear side of the leaf of the lemniscate for a distance of substantially $1/3$ of the length of the leaf of the lemniscate, at which point the

rectangular center portion terminates at both the back and front of the board, the depth of the rectangular center portion being substantially $1/2$ of the length of the leaf of the lemniscate, the front line of the board comprising the front of the rectangular center portion and a line partially convex then becoming concave, like a wave curve, drawn from the front of the rectangular center portion to the point on the front edge of the leaf of the lemniscate cut by a line at right angles to the length of the leaf of the lemniscate, which is substantially $5/6$ of the length of the leaf of the lemniscate from the pole of the leaf of the lemniscate.
